Patented June 28, 1921.

FIG. 1.

FIG. 2.

FIG. 3.

Inventor:
Stuart Noseworthy,

By his attorney,

Charles V. Gooding.

UNITED STATES PATENT OFFICE.

STUART NOSEWORTHY, OF CAMBRIDGE, MASSACHUSETTS.

COMBINATION HAMMER AND HATCHET.

1,383,232.

Specification of Letters Patent. Patented June 28, 1921.

Application filed April 28, 1920. Serial No. 377,283.

To all whom it may concern:

Be it known that I, STUART NOSEWORTHY, subject of King George V of England, residing at Cambridge, in the county of Middlesex and State of Massachusetts, have invented new and useful Improvements in Combination Hammers and Hatchets, of which the following is a specification.

This invention relates to an improved carpenter's tool consisting of a hammer and hatchet combined. The object of the invention is to provide in one tool a hammer and a hatchet, the hatchet blade being detachably fastened to the hammer so that two tools, namely the hammer and hatchet, can be combined in one. Such a tool is of great convenience, and is especially adapted for use by mechanics who are employed in building construction, and being located in inconvenient and high places it is desirable to carry as few tools as possible. In the present invention the hatchet blade can be quickly and securely attached to the hammer or detached therefrom, and the same is provided with a guard which is attached to the hatchet blade in such a manner as to cover the cutting edge of the hatchet when it is not in use so that the hatchet blade can be detached from the hammer and carried in the pocket of the user.

Referring to the drawings,

Figure 1 is a side elevation of my improved combined hammer and hatchet.

Fig. 2 is a sectional elevation taken on the line 2—2 of Fig. 1.

Fig. 3 is a detail section taken on line 3—3 of Fig. 1.

Like numerals refer to like parts throughout the several views of the drawings.

In the drawings 5 is the handle of the tool, 6 the hammer head, and 7 the hatchet blade. One end 8 of the hammer head is cylindrical and is used in the usual manner for hammering nails or the like into position. Said hammer head is also provided with the usual pair of claws 9. The end 10 of said hammer is located opposite the head 8 and is substantially rectangular in cross section as illustrated in Fig. 2. The end 10 of the hammer projects into a slot 11 provided in the rear end of the hatchet blade 7, said slot being located between two jaws 12 and 13. The end 10 of the hammer is fastened to the jaws 12 and 13 of the hatchet blade by a bolt 14, which projects therethrough and

is provided at one end with a head 15, and at the other end with a thumb nut 16 which has screw-threaded engagement with the bolt 14, and thus fastens the head of the hammer 6 and the hatchet blade 7 together. To still further secure the hatchet blade to the hammer head, a pair of oppositely disposed links 17 is provided, said links being pivoted at 18 to the jaw 12, and being also provided with notches 19 adjacent their lower ends which when the links 17 are slung downwardly into the position illustrated in Fig. 1 are engaged by pins 20 fastened to the hatchet blade 7. The links 17 are provided with laterally extending finger pieces 21 for the purpose of conveniently manipulating said links. The cutting edge 22 of the hatchet blade is covered when not in use by a guard 23 which slips onto the hatchet blade and is secured thereto by frictional engagement therewith. The hammer head 6 is attached to the handle 5 by a shank 24 which projects into a slot 25 extending longitudinally of the handle from one end thereof, and is still further fastened to said handle by a pair of screws 26.

Moreover it will be noted that the shank 24 extends longitudinally of the handle from an extension 27 forming a portion of the hammer head, and this extension terminates at the line A, Fig. 1, at a substantial distance below a plane B—B extending at substantially right angles to and transversely of the handle 5, and engaging the lower end of the cutting edge 22 of the hatchet blade 7.

The object of this construction is that if the hammer end 8 or the cutting edge 22, as the case may be, should pass by the object at which a blow is aimed, then the extension 27 would engage said object instead of the wooden handle 5 and prevent said wooden handle from being broken.

I claim:

1. A hammer, a handle therefor, an end on said hammer extending transversely of said handle, a hatchet blade provided with a slot in which said end is adapted to fit, said slot being located between two jaws on said hatchet blade and a bolt extending through said jaws and through said end of said hammer and fastening them together and means to prevent said hatchet blade and hammer from rotating relatively to each other on said bolt.
2. A hammer, a handle therefor, an end

on said hammer extending transversely of said handle, a hatchet blade provided with a slot in which said end is adapted to fit, said slot being located between two jaws on said hatchet blade and a bolt extending through said jaws and through said end of said hammer and fastening them together, and a pair of oppositely disposed links, each of said links pivoted at one end thereof to said jaws 5 and provided with a notch adjacent their op-

posite ends adapted to engage a projection on the other of said jaws.

In testimony whereof I have hereunto set my hand in presence of two subscribing witnesses.

STUART NOSEWORTHY.

Witnesses:

FRANKLIN E. LOW,
CATHERINE M. JOYCE.
